HUBERT LESLIE STRINGER, OF ROCKBEARE HILL, NEAR EXETER, ENGLAND

REFLECTING SIGN

Application filed March 14, 1929, Serial No. 347,053, and in Great Britain March 22, 1928.

This invention relates to advertising and like signs, and it is particularly concerned with that type of sign in which daylight or artificial light is reflected by a mirror to the eyes of passers-by, a stencil being interposed so as to provide any desired advertising or other effect. It is the object of the present invention to provide an improved sign in which successive changes of the advertisement or the like can be produced by means of vibrations.

According to the present invention, in a sign of the type set forth a weight is mounted so as to oscillate under the influence of vibrations to which the sign may be subjected, and is so connected to the sign that, as the weight oscillates, the advertisement or the like is changed. The invention is particularly applicable to signs mounted on motor vehicles, and the oscillating weight and connecting mechanism may then be mounted in the casing of the sign upon the vehicle. The casing containing the stencil and the mirror may be mounted to rock about a pivotal axis, and thus itself act as the oscillating weight.

Preferably the oscillating weight acts to store up energy in an intermediate member, the energy being periodically released to move the stencil, or a mask covering the stencil, through predetermined distances at a time. Conveniently a fixed stencil and a movable mask may be provided, and the mask may be reciprocated by the intermittent action of the intermediate member so as alternately to mask and uncover certain parts of the advertisement or the like. For example the oscillating weight may be arranged to wind up a spiral spring which is periodically released or tripped, and which upon its release rotates the disc or the like connected to reciprocate the mask.

The connecting mechanism between the weight and the mask or stencil preferably includes a driving cord or the like which is fixed at one end to the weight, passes around a pulley or a roller, and is fixed at the other end to a tensioning spring as set forth in the specification of United States Patent No. 1,616,339, to me, dated February 1st, 1927. In cases where the oscillations of the weight

are caused to wind up a spiral spring, this spring may be disposed within, and fixed at one end to the pulley around which the driving cord passes, the other end of the spring being fixed to a disc or the like arranged upon rotation to reciprocate the mask or stencil. When the whole casing of the sign is pivotally mounted so as itself to serve as the oscillating weight, one end of the driving cord may be secured to a fixed point on the motor vehicle or the like and the pulley may be carried by the casing so that the whole moves relatively to the fixed point of attachment of the driving cord as the casing oscillates.

In general, when a driving cord passed around a pulley is employed as described above, it will be desirable to provide a checking cord so wound around the pulley as to prevent any tendency for the latter to rotate in the reverse direction to that in which it is driven by the driving cord.

In order that the invention may be clearly understood and readily carried into effect, some forms of advertising sign constructed in accordance therewith will now be described by way of example with reference to the accompanying drawings in which

Figure 1 is a front view, and

Figure 2 is a plan, partly in section, of one form of sign,

Figures 3 and 4 being cross-sections on the lines III—III and IV—IV respectively of Figure 2, while

Figure 5 is a detailed view of part of the mechanism.

Figure 6 is a rear view;

Figure 7 is a plan, and

Figure 8 an end elevation, viewed from the left of Figure 7, of a modified form of sign, while

Figure 9 is a rear view of another modified sign.

Figure 10 is a perspective view of part of the mechanism of the sign shown in Figures 1, 2, 3, 4 and 5.

Referring first to Figures 1 to 5, a casing of sheet metal is provided having an open front and a top which is partly cut away and covered with a glass plate 2. A mirror 3

is arranged in the casing 1 at an angle of 45° to the horizontal, and is supported by angle brackets 4 placed inside and at the two ends of the casing 1. A glass stencil 5 is placed in an horizontal position beneath the glass plate 2, and is mounted so that it can be slid into position through a slit in the end wall 6 of the casing 1, being provided with a tab 7 by means of which it can easily be withdrawn when desired. This arrangement allows of changes of the advertisement or the like being made with the greatest of ease. A mask 8 in the form of a sliding shutter is mounted on wires 55 so that it can slide over the top surface of the stencil 5, and as shown particularly in Figure 2 it is formed with a number of openings 9. This mask 8 is arranged to slide between two extreme positions, in one of which it masks certain letters on the stencil 5 but admits light through the openings 9 to other letters, while in the second extreme position light is admitted to the first set of letters, the second set being masked. As shown in Figure 2 light is admitted through five openings 9 to the letters forming the word "SIGNS", so that this word appears reflected from the surface of the mirror 3 to the eyes of an observer. The letters forming the word "GLASS" are, however, masked in the position shown in Figure 2, but when the mask 8 is moved to the right into its other extreme position, these letters will be visible in the mirror 3 while the word "SIGNS" will be blocked out.

The driving mechanism by which the mask is moved between its two extreme positions comprises a lead weight 10 mounted at one end of a sheet metal frame 11 pivoted at 12, and supported at its other end by a helical spring 13. When the whole sign is mounted upon a motor vehicle or the like, as the vehicle proceeds the weight 10 will oscillate about the pivot 12 under the influence of vibrations. In order to limit the movement of the weight 10 and to take any shocks due to excessive vibrations, stops 14 surrounded by helical springs 15 are provided. A driving cord 16 is connected at one end to the frame 11 at a point close to the weight 10, is passed around a groove formed in a pulley 17, and is fastened at its other end to a spring 18 which is attached to a dished portion 19 of a sheet metal strip 20 fixed to the casing 1. This sheet metal strip 20 constitutes a frame within which the whole of the oscillating weight and driving mechanism is mounted, so that the latter can be assembled and then fixed in position as a unit within the casing 1.

A checking cord 21, fixed at one end to the part 19 of the frame 20 and at the other end to a tensioning spring 22 also attached to the dished part 19 of the frame 20, is passed around the pulley 17 in the same sense as the driving cord 16, the tensioning springs 18 or

22 being regarded as the point of origin in each case. Thus, as the weight 10 oscillates during its downward movement the pulley 17 is gripped by the driving cord 16 and caused to rotate. The pulley 17 cannot, however, rotate in the reverse direction since any tendency for it to do so is prevented by the checking cord 21 which is caused to pull against its fixed point of connection to the dished part 19 and consequently to grip the pulley firmly. The amplitude of movement of the end of the driving cord 16 is varied by attaching to it a branch cord 23 secured at 24 to the frame 20. By varying the point of connection of this branch cord 23 with the driving cord 16, that is by varying the angle between the cords 16 and 23, the movement of the part of the cord 16 passing around the pulley 17 can be made greater or less than that of the cord connected to the weight so that amplification or reduction of the movement of the weight 10 can be obtained at the pulley 17. Of course, the same amplification or reduction can be obtained by providing a number of different points of attachment for the cord 16 on the frame 11 which carries the weight 10.

It will be appreciated that by the construction just described the pulley 17 is caused to rotate continuously in one direction as the weight 10 oscillates. This pulley 17 is freely mounted upon a spindle 25 mounted in a bearing in the bottom of the casing and in the dished part 19, and carrying at its upper end a disc 26. The pulley 17 is formed in two parts (see Figure 5), a hollow member 27 formed with the grooves in which the cords 16 and 21 are led, and a disc member 28, the two being keyed together by means of a pin 29 carried by the member 27 and entering one of a number of holes spaced around the disc 28 and provided so that the member 27 and disc may be variably positioned relatively to one another. The disc 28 and disc 26 are relatively movable while the disc 26 and spindle 25 move together and the discs 27 and 28 also move together. A spiral spring 30 is disposed within the member 27, being fixed at one end to that member and at the other end to a boss 31 on the spindle 25. Thus, as the pulley 17 rotates, if the disc 26 and spindle 25 are held against rotation the spiral spring 30 will be wound up, with the result that if the disc 26 is then released the spindle 25 and disc 26 will be quickly rotated or flicked through an angle by the action of the spring 30.

In order to hold the disc 26 against rotation while the spiral spring 30 is being wound up, it is formed with a projection 32 which, as the disc 26 rotates, is engaged alternately by two catch members in the form of blade springs 33 formed with shoulders to engage the projection 32. Thus, as long as one of the blade springs 33 is in engagement with

the projection 32 on the disc 26, the spiral spring 30 will be wound up when the weight oscillates. The disc 26 is released, however, every time that the pulley 17 is rotated through 180° by means of a projecting pin 34 carried by the disc 28 of the pulley 17 which engages with the end of whichever blade spring 33 is temporarily in engagement with the projection 32 and forces it clear of the projection, so that the disc 26, under the influence of the spring 30, is flicked through 180° until the projection 32 comes into engagement with the other blade spring 33.

This intermittent motion of the disc 26 is transmitted to the mask 8 by means of an upstanding pin 35 mounted on the disc 26 and engaging within a slot 36 formed in a strip 37 connected to the mask 8. In the arrangement shown in Figure 2 the rotation of the disc 26 through 180° causes the mask 8 to slide from one end of the casing 1 to the other. By arranging the pin 35 on the disc 26 at an angle of 90° relatively to that in which it is shown, the mask 8 may, of course, be reciprocated backwards and forwards in the casing 1 instead of from side to side.

In the modified form shown in Figures 6, 7 and 8, the whole casing 1 is mounted by means of brackets 38 on a board 39 which is pivotally mounted about a spindle 40 on a base 41. The spindle 40 is placed as shown at a distance from one end of the casing 1 equal to about one-third of the length of the casing which thus acts as a pivoted beam having a short end and a long end on opposite sides of the pivotal axis. The short end is pulled down towards the top of the moving vehicle by means of a helical spring 42 which is of such a strength as just to balance the long end which is weighted by means of a weight 43. In order to limit the oscillations of the whole casing, rubber buffers or stops 44 are provided on the base 41.

The mask 8 is moved across the top of the stencil between two extreme positions by means of a mechanism similar to that shown in Figure 5, but in this case the disc 26 and the driving mechanism are enclosed within a box 45 fixed to the end of the casing, and the disc is connected to the mask 8 by means of a connecting rod 46. The driving pulley is mounted as before to turn about a vertical axis, but the driving cord 16 is fastened at one end to the base 41 and passes to the driving pulley over a guide roller 47. Thus, as the entire casing rocks under the influence of the vibrations to which it is subjected, the driving pulley moves relatively to the base 41 with the result that the driving cord 16 grips the pulley and rotates it in a manner similar to that described in connection with Figures 1 to 5.

In the modified form of sign shown in Figure 9, the casing, mask and driving mechanism are similar to those shown in Figures

6, 7 and 8, but the casing 1 is permanently fixed by means of brackets 48 to a fixed base and a separate oscillating weight is provided. As shown this oscillating weight is in the form of a beam 49 pivoted at 50 and restrained at one end by a spring 51. The other end of the beam 49 is guided by a rod 52 which passes through the beam. In order to limit the oscillations of the beam, washers 53 are arranged around the rod 52 on each side of the beam 49, and compression springs 54 are provided around the rod 52 so that as the beam oscillates the washers 53 compress the springs 54.

Having thus described my invention what I claim as new, and desire to secure by Letters Patent, is:—

1. In a reflecting sign, in combination, a mirror exposed to light, a stencil placed at an acute angle to said mirror, a weighted member mounted to oscillate in response to vibration and means actuated by said weighted member for successively obturating the light from different parts of said stencil.

2. In a reflecting sign, in combination, a mirror exposed to light, a stencil placed at an acute angle to said mirror, a weighted member mounted to oscillate in response to vibration, an energy-storing device connected to said weighted member so as to store energy during the oscillations of said weighted member, means for intermittently releasing energy from said energy-storing device and means for applying the energy thus released to obturate the light successively from different parts of said stencil.

3. In a reflecting sign, in combination, a mirror exposed to light, a stencil placed at an acute angle to said mirror, a weighted member mounted to oscillate in response to vibration, a spring, a unidirectional device connecting said weighted member and said spring so as to place said spring under tension during the oscillations of said weighted member, means for intermittently releasing said spring, and means operatively connected with said spring and actuated upon its release for obturating the light successively from different parts of said stencil.

4. In a reflecting sign, in combination, a mirror exposed to light, a stencil placed at an acute angle to said mirror, a weighted member mounted to oscillate in response to vibration, a spiral spring, a unidirectional device connecting said weighted member and said spiral spring so as to wind up said spiral spring during the oscillations of said weighted member, means for intermittently releasing said spring and means operatively connected with said spring and actuated upon its release for successively obturating the light from different parts of said stencil.

5. In a reflecting sign, in combination, a mirror exposed to light, a stencil placed at an acute angle to said mirror, a mask mount-

ed to slide over the surface of said stencil so as to obturate the light from different parts of said stencil, a weighted member mounted to oscillate in response to vibration, 5 and a driving connection between said weighted member and said mask.

6. In a reflecting sign, in combination, a mirror exposed to light, a stencil placed at an acute angle to said mirror, a weighted member mounted to oscillate in response to vibration, two rotatably mounted members, a unidirectional driving connection between said weighted member and one of said rotatably mounted members, a spiral spring fixed 10 at one end to said first rotatably mounted member and at the other end to said second rotatably mounted member, means for holding said second member against rotation, means for intermittently releasing said second member to rotate under the influence of said spring and means operatively connected to said second member for successively obturating the light from different parts of said stencil.

25 7. In a reflecting sign, in combination, a mirror exposed to light, a stencil placed at an acute angle to said mirror, a weighted member mounted to oscillate in response to vibration, means for successively obturating the light from different parts of said stencil and a unidirectional device connecting said weighted member and said obturating means and comprising a pulley, a flexible member encircling said pulley, and having one end connected to said weighted member and a spring applying tension to the other end of said flexible member.

40 8. In a reflecting sign, in combination, a mirror exposed to light, a stencil placed at an acute angle to said mirror, means for successively obturating the light from different parts of said stencil, a weighted member mounted to oscillate in response to vibration, and a unidirectional device connecting said weighted member and said obturating means and comprising a pulley and a flexible member encircling said pulley, elastically tensioned at one end and connected at the other end to said weighted member, said flexible member being flexibly connected at a point intermediate said pulley and said weighted member to a fixed point in said sign.

55 9. Means for changing the matter shown by a reflecting sign comprising the combination with a mirror in said sign of a stencil placed at an acute angle to said mirror, a weighted member mounted to oscillate in response to vibration, means for interposing a mask between parts of said stencil and the reflecting surface of said mirror and a unidirectional driving connection between said weighted member and said interposing means.

60 10. In a reflecting sign, in combination,

a mirror exposed to light, a stencil placed at an acute angle to said mirror, a weighted member mounted to oscillate in response to vibration, a mask, said mask and said stencil being so mounted as to be capable of relative motion, and a unidirectional driving device for imparting said relative motion comprising a pulley, a flexible member encircling said pulley and connected at one end to said weighted member, and a spring applying tension to the other end of said flexible member.

65 11. In a reflecting sign, in combination, a mirror exposed to light, a stencil placed at an acute angle to said mirror, a weighted member mounted to oscillate in response to vibration, a mask, said mask and said stencil being so mounted as to be capable of relative motion, a pulley, a flexible member encircling said pulley and connected at one end to said weighted member, a spring applying motion to the other end of said flexible member, a spiral spring connected at one end to said pulley, a disc connected to the other end of said spiral spring, said disc being mounted so as to be held against rotation, means for intermittently releasing said disc and means for converting the rotary motion of said disc into reciprocating relative motion between said stencil and said mask.

70 12. In a reflecting sign, in combination, a mirror exposed to light, a stencil placed at an acute angle to said mirror, a mask mounted so as to be capable of reciprocating motion over the surface of said stencil, a weighted member mounted to oscillate in response to vibration, a pulley, a flexible member encircling said pulley and connected at one end to said weighted member, a spring applying motion to the other end of said flexible member, a spiral spring connected at one end to said pulley, a disc connected to the other end of said spiral spring, said disc being mounted so as to be held against rotation, means for intermittently releasing said disc and a pin and slot connection between said disc and said mask.

75 13. In a reflecting sign, in combination, a mirror exposed to light, a stencil placed at an acute angle to said mirror, a mask mounted to slide over the surface of said stencil so as to obturate the light from different parts of said stencil, a weighted member mounted to oscillate in response to vibration, means for storing energy during the oscillation of said weight, a disc, means for intermittently releasing said stored energy to rotate said disc and a pin and slot connection between said disc and said mask.

80 14. In a reflecting sign, the combination claimed in claim 1 and means for limiting the amplitude of oscillations of said weighted member.

85 15. In a reflecting sign, the combination

claimed in claim 7 and means for preventing backward rotation of said pulley.

16. In a reflecting sign, the combination claimed in claim 7 and a second flexible member encircling said pulley and secured at one end to a fixed point in said sign and elastically tensioned at its other end.

17. In a reflecting sign, in combination, a mirror mounted so as to receive and reflect light, a stencil mounted in the path of said light, a member for obturating light from parts of said stencil, said stencil and said obturating member being so mounted as to be capable of relative movement, a weighted member mounted to oscillate in response to vibration and means actuated by said weighted member for effecting relative movement between said stencil and said obturating member.

20 18. In a reflecting sign, in combination, a mirror mounted so as to receive and reflect light, a stencil mounted in the path of said light, a member for obturating light from parts of said stencil, said stencil and said obturating member being so mounted as to be capable of relative movement, a weighted member mounted to oscillate in response to vibration, an energy-storing device connected to said weighted member, means for intermittently releasing energy from said energy-storing device and means for applying the energy thus released for effecting relative movement between said stencil and said obturating member.

25 19. In a reflecting sign, in combination, a mirror mounted so as to receive and reflect light, a stencil mounted in the path of said light, a member for obturating light from parts of said stencil, said stencil and said obturating member being so mounted as to be capable of relative movement, a weighted member mounted to oscillate in response to vibration, a spring, a unidirectional device connecting said weighted member and said 30 spring so as to place said spring under tension during the oscillations of said weighted member, means for intermittently releasing said spring, and means operatively connected with said spring and actuated upon its release for effecting relative movement between said stencil and said obturating member.

35 20. In a reflecting sign, in combination, a mirror mounted so as to receive and reflect light, a stencil mounted in the path of said light, a member for obturating light from parts of said stencil, said stencil and said obturating member being so mounted as to be capable of relative movement, a weighted member mounted to oscillate in response to vibration, a spiral spring, a unidirectional device connecting said weighted member and said spiral spring so as to wind up said spring during the oscillations of said 40 weighted member, means for intermittently

releasing said spring and means operatively connected with said spring and actuated upon its release for effecting relative movement between said stencil and said obturating member.

In witness whereof I, hereunto subscribe my name this 5th day of March, A. D. 1929.

HUBERT LESLIE STRINGER.
